T. STOKKE AND A. LARSEN,
OPENING MECHANISM FOR HERMETIC BOXES AND THE LIKE,
APPLICATION FILED JUNE 11, 1919.
1,314,162. Patented Aug. 26, 1919.

FIG. 1.

FIG. 2.

Inventors:
Thorleif Stokke
and Adolf Larsen
by Alfred A. [initials]

UNITED STATES PATENT OFFICE.

THORLEIF STOKKE AND ADOLF LARSEN, OF HILLEVAAG, NEAR STAVANGER, NORWAY,
ASSIGNORS OF ONE-THIRD TO JOHANNES MAELAND, OF HILLEVAAG, NEAR STA-
VANGER, NORWAY.

OPENING MECHANISM FOR HERMETIC BOXES AND THE LIKE.

1,314,162.

Specification of Letters Patent. Patented Aug. 26, 1919.

Application filed June 11, 1919. Serial No. 303,380.

To all whom it may concern:

Be it known that we, THORLEIF STOKKE and ADOLF LARSEN, both of Hillevaag, near Stavanger, in the Kingdom of Norway, have 5 invented certain new and useful Improvements in Opening Mechanism for Hermetic Boxes and the like; and we do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

The present invention relates to an opening mechanism for hermetic boxes or cans of the type in which there is provided in the cover an opening lip or tongue formed 20 in the material of the cover by means of a weakened line and which may be made accessible by an opening key or the like by piercing the cover at the weakened line near the said tongue or lip and bending the same 25 upward.

According to the present invention the weakened line which serves to form the said tongue or lip has the form of a closed 30 curve one part of which extends along the edge of the cover, while another part of the curve is formed by an internally projecting hoop or bow so that there is formed on one side of the cover two adjacent oppositely directed tongues, one or both of 35 which may be used for opening the box.

On the drawing is illustrated a form of the invention.

Figure 1 is a plan of the cover, and

Fig. 2 is a similar plan with one tongue 40 broken up.

The weakened line 1 comprises an inwardly projecting circular curve 2, by means of which there are formed two tongues or lips 4, 5, separated by a narrow strip 3. The tongues may be made accessible in the usual manner by piercing the cover at the weakened line near one end of the tongues and bending the same upward as indicated on Fig. 2. If the opening is not successful with the first tongue, the other one may be used. In order to provide a support for the point of the key when piercing the weakened line bosses 7, 8, 9, 10 may be formed on each side of the same near the tongues 4, 5. 55

Claim:

In an arrangement for opening hermetic boxes and the like a weakened opening line in the cover of the box, said opening line having the form of a double closed curve, 60 the exterior part of which runs along the edge of the cover while the interior part of the curve is formed by an inwardly projecting hoop or bow, said two parts of the curve forming at one or both of their connections an opening lip or tongue which may be utilized for opening the box by 65 piercing the weakened line and bending up the tongue or lip in the usual manner.

In testimony that we claim the foregoing 70 as our invention, we have signed our names in presence of two subscribing witnesses.

THORLEIF STOKKE.
ADOLF LARSEN.

Witnesses:

OTTO ANDERSEN,
TRYGVE SOSO.
